CIGAR MACHINE WRAPPER TRANSFER
CARRIER HEADHjalmar E. Carlson, Brooklyn, N. Y., assignor to
International Cigar Machinery Company, a cor-
poration of New JerseyOriginal application August 16, 1939, Serial No.
290,422. Divided and this application October
2, 1941, Serial No. 413,277

10 Claims. (Cl. 131—105)

This invention relates to cigar machines and more particularly to improvements in wrapper transfer mechanism for use on cigar machines, and constitutes a division of my co-pending application, Serial No. 290,422 filed August 16, 1939, for Cigar machine wrapper transfer mechanism.

It is an object of this invention to provide novel wrapper transfer mechanism which is simple in construction, easily adjustable and of a type especially adapted for use in conjunction with cigar wrapping mechanism in which the cigar wrapper carrier head is adapted to travel along a continuous and closed path during the operation of the machine.

It is a further object of the invention to provide a suction wrapper carrier head which is provided with two compartments divided by an apertured wall and a gravity biased valve for closing the aperture, but which, due to the fact that the head is generally adapted to move along a closed path during the operation of the machine, is provided with a valve stem projecting exteriorly of the casing of the head, and has secured thereto a lever provided with a cam follower so arranged that during the movement of the carrier head to wrapper applying position, the cam follower will engage a cam and move the valve from normally open to closed position for diverting all of the suction into one compartment.

It is a further object of my invention to provide an improved suction wrapper carrier head which is more durable in construction, has fewer parts, is less expensive to manufacture, and will stand up under operating conditions with less wear and tear, and consequently require fewer repairs.

With these and other objects not specifically mentioned in view, the invention consists in certain combinations and constructions which will be hereinafter fully described, and then specifically set forth in the claims hereunto appended.

In the accompanying drawing which forms a part of this specification, and in which like characters of reference indicate the same or like parts:

Figure 1 is a partial side elevation partly in section of the improved wrapper transfer; and

Figure 2 is an end view of the same taken from line 2—2 of Figure 1.

Referring to Figures 1 and 2, the improved wrapper transfer mechanism is mounted on a hollow column (not shown) which may be of the same general type as that shown in the United

States Patent No. 2,235,857, granted March 25, 1941, to Henry H. Wheeler for Wrapper carrier operating mechanism, attached to the base plate of a cigar rolling machine (not shown), and connected to its suction system in the customary manner. The column has a horizontal arm 10 terminating in a bearing 11 in which is journaled a hollow shaft 12 closed at its ends by removable plugs 13 and 14.

10 A gear 15 fixed on the hollow shaft 12 is driven in the same manner as disclosed in said patent above referred to, and therefore, in the interest of brevity, a more detailed showing and description of the same is omitted. To the lower end of shaft 12 is clamped a hollow arm 16 which is provided with a bearing 17 pivotally supporting a hollow arm 18 joined to arm 16 by a bolt 19. The free end of arm 18 forms a bearing for a holder 20 secured to a vertical shaft 21 turning in the bearing and carrying a suction wrapper carrier head 22. From the free end of arm 18 projects a lateral extension 23 which mounts cam follower 24. To the upper end of shaft 21, which extends from the free end of arm 18, is fastened a cam piece 25 carrying a roller 26. The followers 24 and 26 engage in cam tracks provided in the under side of a stationary cam 27 attached to bearing 11, the follower 24 guiding the shaft 21 in a predetermined path and the follower 26 in each position on this path swinging the carrier head 22 to the proper angle for applying the wrapper W to the particular cigar shape for which the cam 27 is designed. The carrier head 22 is adapted to travel through a closed path each cycle of the machine from wrapper receiving to wrapper applying station and back to receiving position, all as disclosed in the above referred to Wheeler patent.

At proper points, the cam 27 has projecting 40 studs carrying followers 28 and 29 adapted to be engaged by the cam piece 25 in the manner described in the above mentioned patent and thereby turning the shaft 21 and reversing the carrier head 22 after the same has delivered the 45 wrapper and is returning to its receiving or pick-up position. In the pick-up position shown in Figure 1, the carrier head 22 rests over the lifter head L of the die, the wrapper W being transferred from the latter to the former in a manner 50 known in the art by a shift of the suction at the moment of contact.

The carrier head 22 is divided by a partition 30 into a forward and a rear chamber which communicate through an opening in the partition 30 having a weighted trap door 31 swinging

on a shaft 32. Shaft 32 projects externally from the carrier head, and on an arm 33 clamped thereto has a cam follower 34, or other suitable valve operating device. The under side of carrier arm 35, by means of a bracket 36, carries a wedge shaped cam piece 37 projecting into the path of follower 34. The weight of trap door 31 is so chosen that the suction in the carrier is not sufficient to lift the same from a stop pin 38 but strong enough to hold it against the partition 30 after being raised into closing position. Thus the trap door 31 in this case is normally open thereby allowing the suction to act over the entire face of the carrier head 22. At a definite point in the path of travel of carrier head 22, when it is desired to shift the suction from the forward holes 39 to the rear holes 40 so as to augment that on the latter, the door 31 is raised by engagement of follower 34 with cam piece 37 and then is held closed by the suction until the same is cut off from the carrier head 22 upon delivery of the wrapper W.

When all but the flag end of the wrapper W has been taken off the carrier head 22, as it is being wound around the cigar bunch at the wrapping station (not shown), a cover 41 movably mounted on the head 22 and normally held in closed position by a spring 42, is opened by engagement with a nozzle (not shown) of a suitable air blast system provided for that purpose.

The invention above described may be varied in construction within the scope of the claims, for the particular device, selected to illustrate the invention, is but one of many possible concrete embodiments of the same. It is not, therefore, to be restricted to the precise details of the structure shown and described.

What is claimed is:

1. In a cigar machine wrapper transfer, a wrapper carrier head movable to and from a wrapper applying position, said head comprising a hollow casing having a wrapper carrying plate and a plurality of chambers in communication with said plate, a wall provided with an aperture located between said chambers, a swinging flap valve arranged to open and close said aperture, said valve being normally gravity biased to open said aperture and maintain suction in both chambers during the movement of said head to wrapper applying position, and means operative at said position for moving said valve to close said aperture and divert all of the suction into one of said chambers, said means including a valve stem extending horizontally through a bearing in said casing, a lever mounted without said casing and fixed to said stem, and traveling means coacting with said lever during the movement of said head for effecting the movement of said valve.

2. In a cigar machine wrapper transfer, a wrapper carrier head movable to and from wrapper applying position, said head comprising a hollow casing, a perforated wrapper carrying plate fixed to said casing and said casing having a plurality of chambers in communication with said plate, a wall between said chambers provided with an aperture, a swinging flap valve arranged to close said aperture, said valve having a horizontal stem mounted pivotally in a bearing through a wall of said casing and being normally gravity biased to keep said passage open and maintain suction in both chambers during the movement of said head to wrapper applying position, an articulated traveling support mounting said head, means for relatively moving said

support and head to transfer a wrapper from a source of supply to wrapping position, a lever fixed to said valve stem exteriorly of said head, and means mounted on said traveling support and moving therewith coacting with said lever during the relative movement between said traveling support and moving head for moving said valve to close said passage.

3. A cigar machine wrapper transfer having the features claimed in claim 1 wherein said last-named means comprises a moving articulated support for said head, a cam mounted on and traveling with said articulated support and constructed and arranged to operate said valve, and a cam follower fixed to said lever and movable therewith into operative relationship with said cam to operate said valve.

4. In a cigar machine wrapper transfer, a traveling suction wrapper carrier head provided with an apertured wall dividing said head into two suction compartments, a normally open valve constructed and arranged to close said aperture during a part of the movement of said head, a traveling support mounting said head for movement to and from a wrapper applying position, and a fixed member mounted on said traveling support and moving therewith and operative upon movement of said head for closing said valve for diverting suction from one of said compartments into the other.

5. In a cigar machine wrapper transfer, a traveling suction wrapper carrier head provided with an apertured wall dividing said head into separate suction compartments, a normally open valve constructed and arranged to close said aperture during a part of the movement of said head, a traveling support mounting said head for movement to and from a wrapper applying position, and means mounted on said traveling support and traveling therewith and operative upon movement of said head to engage said means for closing said valve and diverting suction from one of said compartments into the other.

6. In a cigar machine wrapper transfer, a traveling suction wrapper carrier head provided with an apertured wall dividing said head into separate suction compartments, a normally open valve constructed and arranged to close said aperture during a part of the movement of said head, a traveling frame mounting said head for movement to and from a wrapper applying position, means for moving said head on said frame during the movement of said frame, and means on said frame and movable therewith relative to said head for closing said valve and diverting suction from one of said compartments to the other.

7. In a cigar machine wrapper transfer, a traveling suction wrapper carrier head provided with an apertured wall dividing said head into separate suction compartments, a normally open valve constructed and arranged to close said aperture during a part of the movement of said head, a traveling frame comprising articulated arms, one of said arms mounting said head, and means on another of said arms for closing said valve during the movement of said arms relative to each other to divert all of the suction into one of said compartments.

8. In a cigar machine wrapper transfer, a traveling suction wrapper carrier head provided with an apertured wall dividing said head into separate suction compartments, a normally open valve constructed and arranged to close said aperture during a part of the movement of said

head, a valve trip associated with said valve, a cam follower on said trip, a traveling frame comprising articulated arms, one of said arms mounting said head, and a cam on another of said arms constructed and arranged to engage said follower for closing said valve during the movement of said arms relative to each other to divert all of the suction into one of said compartments.

9. In a cigar machine wrapper transfer, a traveling suction wrapper carrier head provided with an apertured wall dividing said head into two suction compartments, a normally open valve constructed and arranged to close said aperture during a part of the movement of said head, a traveling support for said head comprising articulated arms, means for moving said arms relative to one another to translate said head, and means on one of said arms operative as said

first-named arm moves relative to the other for operating said valve to divert suction from one of said compartments into the other.

10. In a cigar machine wrapper transfer, a traveling suction wrapper carrier head provided with an apertured wall dividing said head into two suction compartments, a normally open valve constructed and arranged to close said aperture during a part of the movement of said head, a traveling support for said head comprising articulated arms, means for moving said arms relative to one another to translate said head, an operating trip for said valve, and a cam on one of said arms operative as said first-named arm moves relative to the other for engaging said trip to operate said valve to close said aperture and divert suction from one of said compartments into the other.

HJALMAR E. CARLSON.
